ARTICLE PICKUP AND DELIVERY APPARATUS

Russell R. McAtee, Joliet, Ill.

Application August 2, 1937, Serial No. 156,908

3 Claims. (Cl. 258—1)

The present apparatus relates to the pickup and delivery of mail, parcels, baggage and other articles to and from a moving vehicle, airplane or the like, and has for its primary object to provide a combined receiving and delivering carrier which is attached to the vehicle and adapted to automatically deliver the package or article to a receiving apparatus on the ground and to subsequently pick up another article or package from the same receiving apparatus.

An important object of the present invention is to provide a combined carrier of this character adapted for movement into and out of position through an opening in the moving vehicle for the pickup and delivery of the article when the carrier is positioned outwardly of the vehicle and to provide means for moving the carrier into the vehicle in order to conveniently place the package or article thereon or to disengage the picked up article therefrom.

A still further object is to provide an apparatus of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view of the combined pickup and receiving carrier with parts of the airplane or other vehicle broken away and shown in section.

Figure 2 is a top plan view.

Figure 3 is a vertical sectional view through the releasing mechanism.

Figure 4 is a fragmentary top plan view of a modified form of releasing mechanism.

Figure 5 is a side elevational view of a modified construction of the supporting arms for the carrier, and

Figure 6 is a rear elevational view of the carrier.

Referring now to the drawings in detail, the numeral 5 designates the carrier generally, which includes a plate 6 to the under side of which the casting 7 is formed.

Formed on the bottom edge of the casting is a hook member 8 which opens in a forward direction and has a pivoted catch 9 arranged to swing inwardly of the hook and to have its free end

engage the end of the hook to close the hook after an article has been engaged thereby.

At the rear end of the casting is formed the releasing mechanism designated generally at 10 which includes the top member 11 which is integral with the casting and the bottom member 12 which is pivoted at its forward end to the casting and having a free end releasably held upwardly against the upper member 11 by a bolt 13. The upper member 11 is formed with a vertically extending opening 14 through which the bolt extends and the free end of the pivoted member 12 is formed with a longitudinally extending slot 15 extending through the end of the member and through which the bolt 13 also extends, the bottom of the bolt being formed with a cross-head 16, adapted when positioned cross-wise of the slot 15, to retain the pivoted member 12 in an upward position against the member 11.

The bolt 13 is formed with a shoulder 17 against which an expansible coiled spring 18 is adapted to abut to yieldably urge the bolt in an upward position to prevent idle rotation thereof. The upper end of the bolt 13 is formed with a laterally projecting arm 19.

The top of the plate 6 is formed at its forward edge with a block 20 to which a rod 21 is pivotally connected at one end, the other end of the rod being pivoted as at 22 to the bottom 23 of a fuselage or cabin of an airplane provided with an opening 24. A link 25 connects the rod 21 with the block 20 of the carriage. To the rear of the plate 6 is provided a pair of upstanding lugs 26 to which is attached a cable 27 leading upwardly into the airplane through the opening 24 for connection to a suitable hoisting mechanism (not shown) whereby the carriage may be raised upwardly and lowered into and out of the opening 24. When the carriage is raised upwardly into the opening the pivoted connection at its forward end will permit the carriage to be inverted into the position as shown by the dotted lines in Figure 1 of the drawings.

The opposed faces of the members 11 and 12 are formed with a recess 28 substantially pear-shaped in cross section and adapted to receive a correspondingly shaped lug 29 pivoted on a ring 30 from which a mail-bag 31, or other article, may be suspended.

Projecting outwardly from opposite sides of the plate 6 is a pair of spaced parallel arms 32 on which rollers 33 are journaled, the rollers being adapted to ride upon a pair of spaced guides (not shown) of a suitable receiving apparatus.

In the modified form of the invention shown in Figure 5 the guide arms and rollers 32 and 33 are dispensed with and in lieu thereof a pair of spaced parallel bars 34 are provided which project outwardly from one side of sockets 35 for supporting the carrier in a position outwardly from the side of a railway mail car or the like. The bars 34 are secured in adjusted position in the sockets by set screws 36.

10 In the operation of the device the receiving mechanism, which is positioned on the ground, is provided with an upstanding pin (not shown) raised in the path of the arm 19 so that upon engagement therewith the bolt 13 will be rotated, 15 moving the cross-head 16 longitudinally with respect to the slot 15 whereby to permit the pivoted member 12 to drop downwardly, thus releasing the mail bag or other article from the carrier.

20 In the modified form of the invention illustrated in Figure 4 of the drawings, the bolt 13 is provided adjacent its upper end with a gear 37 with which a gear segment 38 is engaged, one edge of the gear segment projecting outwardly 25 laterally from the carrier into a position to operate the bolt in the same manner as that heretofore explained.

It is believed the details of construction and manner of operation of the device will be readily understood from the foregoing without further detailed explanation.

Having thus described the invention, what I claim is—

1. In an article delivery and pick-up apparatus, a carrier attached to a moving machine, an article pick-up member at the front end of the carrier, an article delivery mechanism at the rear end of the carrier and including a latch device normally holding the article in the 35 delivery mechanism and operable upon contact with an object in the path of the delivery mechanism to release the latch, said latch device comprising an article supporting member pivoted 40

at its forward end to the carrier, said member having a slot in its rear end, a vertical shaft rotatably carried at the rear end of the carrier and having a T-head at its lower end, said shaft being projected through the slot with the 5 T-head crosswise thereof to secure the member in closed position and a trip arm carried by the shaft for rotating the same to release the member therefrom.

2. In an article delivery and pick-up apparatus, a carrier attached to a moving machine, an article pick-up member at the front end of the carrier, an article delivery mechanism at the rear end of the carrier and including a latch device normally holding the article in the delivery mechanism and operable upon contact with an object in the path of the delivery mechanism to release the latch, said latch device comprising an article supporting member pivoted 10 at its forward end to the carrier, said member having a slot in its rear end, a vertical shaft rotatably carried at the rear end of the carrier and having a T-head at its lower end, said shaft being projected through the slot with the T-head 15 crosswise thereof to secure the member in closed position and a trip arm carried by the shaft for rotating the same to release the member therefrom.
